TRANSVERSE TRAVELING WAVE AMPLIFIER

Robert S. Bailey, New York, N. Y., assignor to
 International Standard Electric Corporation,
 New York, N. Y., a corporation of Delaware

Application February 4, 1948, Serial No. 6,284

6 Claims. (Cl. 315—39)

1

The present invention relates to a travelling wave amplifier tube and more particularly to that variety of travelling wave amplifier tube in which an electromagnetic wave exchanges energy with an electronic stream flowing transversely to the direction of propagation of the electromagnetic wave.

Travelling wave amplifiers employing the negative resistance principle are well known in the art. Most of these amplifiers amplify substantially equally well in either direction giving rise to certain disadvantages, especially those of ringing or oscillating. Another disadvantage of the travelling wave amplifier of the prior art is that considerable energy is taken from the incident electromagnetic wave in order to control the motion of electrons which contribute no energy to said wave.

It is an object of the present invention to overcome these difficulties and to provide a travelling wave amplifier in which electrons are injected into the amplification space substantially only at times favorable for energy exchange from the electron stream to the electromagnetic wave.

The method used to obtain amplification in the transverse travelling wave amplifiers of the present invention is to arrange the tube structure in such a way that energy interchanges take place between an electromagnetic travelling wave field and a stream of moving electrons, the greater interchange of this energy being from the electrons to the field. The principle utilised in the present invention is to accelerate electrons by a fixed potential field into a region where they may react with an electromagnetic travelling wave field. It is clear that if any one of such electrons possesses a given kinetic energy corresponding to a given velocity, say V_e , and by some agency this V_e is reduced, the kinetic energy of this electron is reduced proportionally to the difference between the squares of the two velocities in question.

By the principle of conservation of energy this energy is imparted to the agency causing the action and thus, if this agency is an electromagnetic wave, the wave will be augmented in energy. The inverse action, increasing electron velocity, results in loss of energy to the electron and is therefore to be avoided.

According to the present invention both the magnetic and electric components of an electromagnetic wave are used to control the direction and velocity of an electron stream in such a way that many of the disadvantages of the travelling wave amplifier of the prior art are eliminated.

2

It is clear that an electron remaining in an electromagnetic field for an integral number of cycles of that field will be, in general, unaffected in total energy. An electromagnetic field can be reinforced by a given moving electron only during a half cycle of the electromagnetic wave unless the electron velocity vector is reversed in synchronism with the wave. Thus, amplification of the travelling wave amplifier may occur when an electron is in the field for any integral number of cycles plus $\frac{1}{2}$ cycle. But, in another way, a travelling wave amplifier which produces amplification at a wave length λ_1 will also amplify a band of wave lengths up to λ_1 and then will amplify relatively narrow bands at approximately

$$\frac{\lambda_1}{2} + \frac{1}{2}, \frac{\lambda_1}{3} + \frac{1}{2}$$

20 The above mentioned and other features of the invention and the manner of attaining them will become more apparent and the invention itself will be best understood by reference to the following description of several embodiments of the invention taken in conjunction with the accompanying drawings wherein:

Figs. 1 and 2 are transverse and longitudinal sections, respectively, of a coaxial line used to illustrate the principles of the invention;

25 Fig. 3 represents a longitudinal cross section of an embodiment of the invention utilizing a coaxial line;

Figs. 4 and 5 are orthogonal, longitudinal sections of an embodiment of the invention utilizing a wave guide;

30 Figs. 6 and 7 are transverse and longitudinal sections, respectively, of a second embodiment of the invention utilizing a wave guide.

35 Referring to Figs. 1 and 2, a coaxial or transverse electromagnetic transmission line is shown together with symbols indicating the direction and polarity of the electric and magnetic vectors in this transmission line. The electric lines are indicated by the solid lines on the drawings while the magnetic lines are indicated by the dotted lines on the drawing. Propagation of the transverse electromagnetic mode requires two conductors 1, 2 such as the coaxial transmission line shown in Figs. 1 and 2 or the parallel transmission line well known in the art. This mode-type 40 cannot be propagated in a wave guide and hence is given a separate classification and will be first considered.

45 The transverse electromagnetic type is characterized by transverse electric and magnetic fields 50 as shown in Figs. 1 and 2, electromagnetic wave

propagation being in a direction perpendicular to both of the vectors according to the well known Poynting relation. It is seen in Figs. 1 and 2 that the electric and magnetic lines are reversed in direction each half-wave length along the longitudinal dimension of the coaxial transmission line. The transverse travelling wave amplifier of the prior art has operated on the principle that electrons emitted from, say the inner conductor of such a coaxial transmission line, will on the average, be decelerated before reaching the outer conductor, generally held at a high direct current potential. According to the present invention the magnetic force lines are also utilized to provide focusing and control of emitted electrons from either conductor in order to obtain a higher efficiency.

Referring to Fig. 3 a coaxial transverse electromagnetic mode type is utilized to obtain an amplification according to the principles of the present invention. A coaxial line consisting of an outer conductor 3 and inner conductor 4 and an auxiliary conductor 5 inside conductor 4 and provided with electron emissive electrodes 6 is provided. The openings in conductor 4 are provided with the electron emissive electrodes 6 positioned so that electrons emitted from electrodes 6 will not normally emerge into the space between electrodes 3 and 4. In operation the electromagnetic wave to be amplified is impressed by known means into the coaxial lines consisting of conductors 3 and 4. An auxiliary wave, which may be derived from the main wave, is impressed between the conductors 4 and 5. A fixed direct current potential may be established between electrodes 5 and 4 such that electrons emitted from electrode 6 will be attracted toward 4 but will not, in the absence of input electromagnetic waves, emerge into the space between electrodes 3 and 4. However, when the travelling wave amplifier tube is placed in operation and an auxiliary wave energizes the inner coaxial line consisting of conductors 4 and 5, it will be understood that a new force other than the applied static D. C. potential acts upon electrons emitted from electrode 6. This force is due to the magnetic field intensity vector of the incident radio frequency waves and will operate to deflect the electrons into a curvilinear path without altering their velocity due to the static potential between electrodes 4 and 5. Electric field lines due to the main electromagnetic waves between conductors 3 and 4 are shown schematically by 7. It is seen that these lines reverse in direction and increase in magnitude periodically each half wave length. It is well known to those skilled in the art that the corresponding magnetic intensity line also reverses in direction and magnitude each half wave length. It will then be clear that electrons emitted from electrode 6 due to an auxiliary wave travelling in a direction as shown in the diagram, from left to right, will experience a magnetic force tending to turn the electrons into the gaps in electrode 4 which have been so positioned that electrons from electrode 6 cannot, in the absence of an exciting field, reach the interelectrode space 3, 4. However, under the influence of an electromagnetic field travelling in the direction stated, it will be clear that the turning action of the magnetic intensity vector of this field will cause electrons to be deflected thru the opening of electrode 4 and into the interspace between electrodes 3 and 4 of the main transmission line. Between these electrodes is maintained a static D. C. accelerating potential chosen to be of such

magnitude that the electronic transit time will be an integral number of half waves of the incident electromagnetic waves plus $\frac{1}{2}$ cycle as stated above. Under these conditions it will be understood that amplification will occur in the main transmission line 3, 4 with a minimum loss of energy; that is no electrons will appear in the space 3, 4 at times unfavorable for deceleration of the electrons. A pair of conductors 8 is shown for the purpose of heating the emissive electrode 6 to the desired temperature. It will at once be apparent that an electromagnetic wave travelling in the opposite direction, that is from right to left in the figure, will not be amplified since, due to the reverse direction, all of the electric and magnetic vectors will be reversed and electrons emitted from electrode 6 will impinge on electrode 4 and will not appear in the main transmission line, 3, 4.

In Figs. 4 and 5 a wave guide embodiment of the present invention is shown wherein a main wave guide 9 is provided with a foraminated electrode 10 and emissive electrode 11 connected to energization means 12. Electric field intensity lines are shown and it is seen that again both the electric and magnetic intensity reverse each half wave along the direction of propagation of electro-magnetic energy in the guide. As in Fig. 3, the electron emissive electrodes 11 are so placed with respect to the foraminated structure 10 and the potential difference between the electrodes so adjusted that electrons emitted from 11 in the absence of incident radio frequency energy all impinge upon electrode 10 and are there collected, none of them appearing in the main wave guide transmission line 13. Operation proceeds generally as recited above. An auxiliary or control wave preferably derived from the main wave to be amplified energizes the wave guide defined by electrodes 10 and 12 while the main wave to be amplified energizes the space 13. Again the magnetic wave vector of the electromagnetic field in the wave guide 10, 12 causes the electrons emitted from the electrode 11 to be turned into a curvilinear path resulting in their emission into the space 13. The wall 9 of the main wave guide is held at a high direct current potential in order to collect electrons emitted into 13. This direct potential is chosen in conjunction with the potential used to accelerate electrons from electrode 11 to electrode 10 and the electron transit time as described above. It is clear that amplification in the reverse direction, that is from right to left in the figure, will not occur for the same reasons given in connection with Fig. 3.

Referring to Figs. 6 and 7 a wave guide operating in the $TE_{1,1}$ mode is shown provided with means for amplification according to the principles of the present invention. Again electric field lines are shown by solid lines and the magnetic field lines by dotted lines on the figure. The main guide line 14 is provided with emissive electrodes 15 energized by conductors 16. A collector plate 17 is positioned oppositely to the emissive electrode 15 and insulatively but capacitatively connected to the wave guide wall 14. A foraminated structure 18 is provided in proximity to the electron emissive surfaces 15 and operated at a positive direct current potential as indicated at 20. The openings in electrode 18 are again so positioned with respect to electron emissive electrode 15 that electrons can not emerge into the main wave guide transmission space 19 except in the presence of an electromagnetic wave in a predetermined direction down,

the wave guide 14. Operation proceeds generally as in the preceding cases.

While I have described above the principles of my invention in connection with specific apparatus and with specific electromagnetic mode types in specific transmission lines it is to be clearly understood that this description is made only by way of example and not as a limitation to the scope of my invention.

What is claimed:

1. A transverse traveling wave amplifier comprising means defining an electromagnetic wave path and a cathode comprising a plurality of emissive elements mounted adjacent said path to project electrons transversely across said path, an electron focusing means to render said amplifier unidirectional comprising a control electrode mounted between said cathode and said path and provided with apertures and means connected to said control electrode for applying a direct current potential thereto to attract electrons from said cathode, each emissive element of said cathode being disposed in offset relation with respect to an adjacent aperture and said control electrode being coupled to said wave path for applying a portion of said electromagnetic wave between said cathode and said control electrode to deflect electrons through said apertures during one half cycle of the wave.

2. An amplifier according to claim 1 wherein said cathode comprises a plurality of elements mounted adjacent one edge of the apertures in said control electrode whereby electrons deflected in one direction will pass through said apertures and those deflected in the other direction will impinge on said control electrode.

3. A transverse travelling wave amplifier comprising an electromagnetic wave path, a cathode mounted adjacent said path to project electrons transversely across said path, a control electrode mounted between said cathode and said path and provided with apertures, said control electrode being coupled to said wave path for applying electromagnetic waves between said cathode and control electrode, said coupling being adapted to provide a magnetic component of said wave that will deflect electrons from said cathode in the direction of travel of waves in

said path or in the reverse direction, said cathode including a plurality of electron emissive electrodes mounted in offset relation with respect to said apertures so that electrons pass through said apertures only during one half cycle of said wave.

4. A transverse traveling wave amplifier comprising an electromagnetic wave path, a cathode mounted adjacent said path to project electrons transversely across said path, a pair of foraminated electrodes mounted between said cathode and said path and coupled to said wave path for applying an electromagnetic wave therebetween, said coupling being adapted to provide a magnetic component of said wave that will deflect electrons from said cathode in the direction of travel of waves in said path and in the reverse direction, said cathode including a plurality of electron emissive electrodes mounted in spaced relation with respect to said foraminated electrodes such that electrons are deflected through said foraminated apertures only during one half cycle of said wave.

5. An amplifier according to claim 4 wherein said wave path is a coaxial transmission line and said foraminated electrodes are cylindrical and form a coaxial transmission line with one another, the one of said foraminated electrodes adjacent said cathode forming one of the conductors of said first-mentioned transmission line.

6. An amplifier according to claim 1 wherein said wave path comprises a wave guide, said cathode and control electrode being mounted therein, and a collecting electrode is mounted in said wave guide transversely across from said cathode and control electrode.
